UNITED STATES PATENT OFFICE.

THOMAS F. GAYNOR, OF LEXINGTON, KENTUCKY, ASSIGNOR TO THE LEXINGTON MANUFACTURING COMPANY, OF SAME PLACE.

FIRE-ALARM SIGNAL.

SPECIFICATION forming part of Letters Patent No. 335,027, dated January 26, 1886.

Application filed April 18, 1885. Serial No. 162,718. (No model.)

To all whom it may concern:

Be it known that I, THOMAS F. GAYNOR, a resident of Lexington, in the county of Fayette and State of Kentucky, have invented certain new and useful Improvements in Fire-Alarm Signals, of which the following is a specification.

My invention relates to that class of fire-alarm-signal devices which is employed to transmit or send out over one or more circuits any desired number or alarms by an apparatus which may be readily set in motion by the operator by adjusting the index and starting the clock-work train to indicate any desired number or any given signal.

The object of this invention is to produce improved mechanism which can be set in motion to automatically repeat any number of times any desired signal, and to send the same over one or more circuits, all of which will be fully set forth in the description of the accompanying drawings, making part of this specification, in which—

Figure 1 is a front elevation of my improvement placed in a suitable box. Fig. 2 is an enlarged front elevation, with the outside cover of the box removed, partly in section. Fig. 3 is a detail sectional view of the setting mechanism. Fig. 4 is a diagram showing the circuit-connections. Fig. 5 is a modification of the circuit-breaking device. Fig. 6 is a plan view of the dial-plate.

A represents the frame-work of a suitable box, which is adapted to be set in any convenient position at the main station of a fire-alarm system.

a a' represent dial-faces, which are numbered to the right from "naught" upward.

Within the box is placed a clock-work train consisting of a windlass, 1, cord-weight 2, and spur-gears 3 4 5 6.

7 represents an escapement, and 8 a weight which is adapted to be regulated upon the pendulum-rod 9 to control the speed of the revolving drum.

10 represents a tripping-arm which is mounted on shaft 11 of windlass 1. The clock-work train is set in motion by moving the tripping-arm 21, and it operates generally in the manner shown and described in my application of November 18, 1884, Serial No.

148,229. Shaft 13, which is driven by gear 4, carries a revolving cylinder 14.

15 represents a gear keyed to said shaft, driving gear 16, which carries a similar cylinder, 17. Additional cylinders and gears may be employed, as desired. Cylinder 14 is placed opposite dial a, and is provided at regular intervals, b, with teeth c, which serve as circuit-breakers, as shown in section, Figs. 3 and 4. 55

The series of teeth shown in section indicate the number 32, and these teeth are opposite the number 32, Fig. 6, of dial a, and a number of circuit-breakers corresponding to the numerals are arranged along the face of the 65 cylinder, so as to come opposite their proper numerals on the dial-plate. One or more spring circuit-breakers are employed, so as to be set in relation to any one of the numerals on the dials a a' a'', to send the alarm whenever 70 the clock-train is in motion. This clock-train operates after the manner shown in my said former application, but the contact-spring is made adjustable in the following preferred manner: The contact-spring C is mounted 75 upon a sliding stock, B, d being an insulator, d' a binding-post, d'' a set-screw passing through the stock B for raising the rubber to adjust the tension of the spring-arm C.

D E represent guide plates or ears, which 80 are attached to the shank of stock B each side of the dial-plate a, which is provided with a longitudinal slot, in which the shank of stock B rests and slides laterally.

e represents an index-finger to aid in setting the mechanism.

F represents a handle attached to the shank of stock B, so that the device may be slid laterally in the slot t of the dial-plate a to bring the contact-spring arm C into contact with the 90 circuit-breaking projections of any desired number on the cylinder 14. Cylinder 17, and each additional cylinder, has similar metallic circuit-breaking protuberances, e, of numbers higher than those on cylinder 14, and it is 95 provided with a similar dial and circuit-breaking spring, C, attached to the setting mechanism D F.

In order that the signaling mechanism may be employed to send the signals over a different number of circuits—as, for instance, to ring one or more tower-bells, to ring an alarm at

the mayor's office, station-house, water-works, or other different points which are in different circuit-connections—I have provided a multiplex armature, 18, for relay H. The 5 coils of the relay are connected in circuit with the circuit-breaking cylinders, as represented by diagram, Fig. 4. I representing the battery of the signaling-circuit, and J K L M representing batteries of repeating-circuits operated by the armature 18 of relay H; but the circuit which is operated by cylinders and battery I may also be used to operate bells and other signal mechanism as a main circuit.

10 *i r s t* represent contact-points in metallic connection with the batteries J K L M.

15 *o v l n* represent contact-points mounted upon the armature 18 of the relay, and in metallic connection with the opposite poles of the batteries J K L M from that of the contact-points *i r s t*. When the battery I is closed by the contact of the teeth *e* with the spring-arm C, armature 18 is attracted by relay H, and batteries J K L M are closed by the contact of points *o v l n* with points *i r s t*, and 20 the signal by the revolving of the cylinder is repeated simultaneously through all the circuits connected by the multiple armature of the relay.

25 I do not wish to limit myself to the number of circuits which may be connected through the armature of the relay, as any desired number may be employed.

30 20 represents a key placed outside of the box A and in the main-battery circuit I, which may be operated to close the circuit when the cylinders are at rest, and telegraph communications through the circuits operated by the batteries J K L M, as well as through the circuit of the main battery I.

35 40 Instead of employing the teeth in cylinder, as shown in Figs. 2, 3, 4, I have made a modification (shown in Fig. 5) representing a cylinder provided with teeth *m*, with which the circuit-breaker C is in contact.

45 45 O represents a rubber or insulator made to surround the cylinder, insulating the teeth from each other, so as to prevent accidental contact if the point of the circuit-breaker is brought in contact with the periphery of the 50 cylinder.

The operation of the key 20 and of the clock-work train is similar in operation to that shown in my said former application.

21 represents a spring-trigger for arresting and starting the movement of the tripping-arm 10 and the clock-work train; or the clock-work train may be set in motion by means of a key operated in the manner described in my application, Serial No. 148,230, filed November 18, 1884. 60

I claim—

1. In combination with a clock-work train having an arm upon its main shaft, a pivoted spring-actuated lever engaging with said arm, a series of cylinders, 14 17, driven by said train and having upon their peripheries circuit-breaking teeth, spring-arms C, resting upon said cylinders, and stocks B, carrying the spring-arms and adjustable longitudinally relatively to the cylinders, substantially as 70 described.

2. In combination with a clock-work train, one or more cylinders having upon their peripheries several separate series of circuit-breaking teeth, each series being adapted to 75 sound a separate signal, a main battery in circuit-connection therewith, a spring-arm, C, to each cylinder, and adjustable longitudinally upon said cylinders, and dials *a*, upon which said arms are adjusted, substantially as 80 described.

3. In combination with a main battery, I, having circuit-connection with one or more circuit-breaking cylinders, a circuit-closing spring-arm adjustable longitudinally upon 85 said cylinders, a relay interposed in said circuit, an armature having a series of contact-points, each having connection with one pole of a separate battery, and a series of contact-points in connection with the other pole of 90 said battery, substantially as described.

In testimony whereof I have hereunto set my hand.

THOMAS F. GAYNOR.
